Primary Examiner — T. Chase Nelson*Assistant Examiner* — Ania Aman(74) *Attorney, Agent, or Firm* — Renner, Otto, Boisselle & Sklar, LLP(57) **CLAIM**

The ornamental design for a filter drier, as shown and described.

DESCRIPTION

FIG. 1 is a perspective view of a filter drier showing our new design.

FIG. 2 is a front view thereof, a rear view, a top view, and a bottom view appearing the same as the front view; and, FIG. 3 is a left side view thereof, a right side view being a mirror image of the left side view.

In the drawings, the broken lines depict unclaimed subject matter only and form no part of the claimed design.
